UNITED STATES PATENT OFFICE

CHARLES S. SMITH, OF MILWAUKEE, WISCONSIN, BY JUDICIAL DECREE OF DISTRIBUTION AND ASSIGNMENT TO GALBRAITH MAYO SMITH, TRUSTEE, OF SHOREWOOD, WISCONSIN

MACHINE FOR TRUING GRINDING WHEELS

Application filed January 20, 1926. Serial No. 82,562.

My invention relates to an improved machine for truing the surfaces of grinding wheels, particularly of the type provided with grinding surfaces in the form of helices, 5 signed for the grinding in circumferential bands or zones, and in successive longitudinal sections, a shaft which is provided with a number of equally spaced longitudinally extending splines. Such a grinding machine is 10 closed in my prior application filed Aug. 30, 1924, Serial No. 735,221 on which Patent No. 1,593,272, was granted July 20, 1926.

In the operation of the grinding machine, the grinding wheel provided with a grinding 15 surface in the form of a helix is caused to engage with the splines of the shaft to be corrected, and in the rotation of the grinding wheel, the splined shaft is rotated in synchronism therewith so that the splines are 20 corrected in circumferential bands or zones, the shaft being advanced upon completion of one section or band so as to present another successive section or band to the action of the grinding wheel.

25 At times it becomes necessary to true up the grinding wheel in order to insure accuracy in the work operated upon, and it is the purpose of my present invention to achieve this result. The invention resides in a pressure roller of hardened metal having a surface which is formed as the complement of the 30 grinding roller and which is adapted to be brought into engagement therewith at the desired times. The surface pressure of the 35 two rollers is regulable, and when brought together, a joint rotation is effected at the same surface speed. As a result of the pressure exerted during the rotation of the two rollers, the surfaces of the grinding roller 40 are accurately trued up in a very expeditious manner.

The pressure or truing roller is journaled 45 in bearings in a slide which latter may be moved vertically by means of an adjusting screw. The shafts carrying the two rollers are connected by a novel system of gears whereby such rollers are caused at all times to rotate in the same direction at a uniform rate of speed.

50 The gears referred to receive their motion

from the shaft of the grinding roller, and the engagement of the said gears so as to preserve a correct timing is maintained, even though the surfaces of the two rollers are out of engagement.

55 The novel features of the invention will now be specifically described, and then pointed out in the appended claims.

In the accompanying drawings:

Figure 1 is a view in side elevation showing 60 my improved machine, parts being in section to show certain details of construction.

Fig. 2 is a right hand end view in elevation 65 of the machine shown in Fig. 1, parts being sectioned for a like purpose.

In the drawings, the numeral 10 designates the frame or pedestal of the machine, in the upper part of which the shaft 11 carrying the grinding wheel 12 is mounted in journals 13. The said shaft may be driven by a 70 band pulley 14 fixed thereon.

A bracket 15 guided for vertical movement upon the frame 10 is adjusted as to position by a screw 16 stepped in a bracket 17 at its lower end, its upper end being threaded 75 into the bracket 15. A bed 18, upon which is mounted the devices for supporting the shaft 19, the splines of which are to be corrected, is guided for lateral movement longitudinally on the bracket 15, and may be 80 moved by operation of the hand wheel 20. The devices supporting the splined shaft may be moved longitudinally on the bed 18, through the operation of the hand wheel 21, 85 so as to bring the successive bands or zones of the shaft 19 into engagement with the grinding surface of the wheel 12.

90 A spiral gear or worm 22, on the end of the shaft 11 is in engagement with a like gear 23 on the shaft 24, extending at an angle to the shaft 11. At its other end, the shaft 24 is provided with a bevel gear 25 engaging a like gear on the rear end of the shaft 26. The front end of the shaft 26 is provided with 95 a spiral gear or worm 27, in mesh with a like gear 28 on the splined shaft 29, through which rotation is imparted to the shaft 19, the splines of which are to be corrected. In this manner the movements of rotation of the 100

grinding wheel 12 and the splined shaft 19 are synchronized.

Surmounting the frame or pedestal 10 is a standard 30, on which is guided for vertical movements a slide 31. The slide 31 is provided with bearings 32 and 33, in which is journaled the shaft 34 of the truing wheel 35. The shaft 11 of the grinding wheel 12 and the shaft 34 of the truing wheel 35 are connected by four pinions 36, 37, 38 and 39. The pinion 36 is fixed upon the shaft 11 and is held in engagement with the pinion 37 by means of links 40 and 41, embracing the shaft 11 and the floating stud 42 upon which the pinion 37 is mounted. The pinion 39 is fixed on the shaft 34 and is in engagement with the pinion 38, which latter is mounted on a stud 43 fixed in an extension 44 of the slide 31. The pinions 37 and 38 are held in engagement by means of links 45 and 46, which embrace both the floating stud 42 and the fixed stud 43. A screw 47 mounted in the upper end of the standard 30 is restrained against longitudinal movement, and its lower end is threaded into an ear 48 formed on the slide 31. By means of a hand wheel 49, the screw 47 may be rotated so as to impart vertical movement to the slide 31 which supports the truing wheel 35. The links 40, 41 and 45, 46 pivot at their connected ends on the floating stud 42, thus compensating for the approaching and receding movements of the truing wheel 35.

By rotating the screw 47 through the hand wheel 49, the truing wheel 35 is brought into engagement with the grinding wheel 12. The parts being in rotation, the pressure exerted by the truing wheel 35 upon the surface of the grinding wheel 12 will restore in a very accurate degree the conformation of the latter. The pressure of the truing wheel 35 will be maintained for such time and with such force as may be necessary to recondition the grinding wheel 12. After the desired end has been attained, the truing wheel 35 will be withdrawn by reversing the screw 47, and the work of correcting the splined shaft 19 may be resumed.

The truing wheel 35 may be formed as a tubular member of chilled iron having great density and hardness. It may be mounted upon the shaft 34, and retained in position by a demountable ring 51, attached to the end of the drum 53, and serving to clamp the tubular truing wheel 35 against a flange 52 at the other end of the drum. The grinding or spline correcting wheel 12 may be mounted in a similar manner with respect to the shaft 11. In the first assembly of the wheels 12 and 35, their complemental surfaces should be brought into exact register.

Having thus described my invention, what I claim and desire to secure by Letters Patent of the United States, is:

1. In a machine of the class described, a

grinding wheel having a grinding surface constituted as a helix, a truing wheel having a surface complemental to that of the grinding wheel, means connecting the said wheels for rotation in unison, and means for exerting pressure by the truing wheel upon the grinding wheel.

2. In a machine of the class described, a grinding wheel having a grinding surface formed as a helix for correcting the splines of a shaft, means connecting the grinding wheel and the shaft whereby such wheel and shaft are rotated in synchronism, a truing wheel having a surface complemental to that of the grinding wheel, gearing connecting the said wheels to rotate them in unison, and means for exerting pressure by the truing wheel upon the grinding wheel.

In testimony whereof, I have signed my name at Milwaukee, this 12th day of January, 1926.

CHARLES S. SMITH.
